UNITED STATES PATENT OFFICE

169,364

PINUP LAMP

Albert Epstein, Boston, Mass., assignor to
Louis Epstein, Boston, Mass.

Application December 6, 1952, Serial No. 22,589

Term of patent 7 years

(Cl. D48—4)

To all whom it may concern:

Be it known, that I, Albert Epstein, a citizen of the United States of America, residing at Boston, county of Suffolk, Commonwealth of Massachusetts, have invented a new, original, and ornamental Design for a Pinup Lamp, of which the following is a specification, reference being had to the accompanying drawing, forming a part thereof.

In the drawing:

Fig. 1 is a front elevational view of a pinup lamp, showing my new design.

Fig. 2 is a plan view thereof.

Fig. 3 is a side elevational view thereof.

Fig. 4 is a bottom view thereof.

I claim:

The ornamental design for a pinup lamp, substantially as shown.

ALBERT EPSTEIN.
